DESIGN FOR A COMBINED LAMP STAND AND
ASH TRAY

Leonard D. Cherneff, Seattle, Wash.

Application April 26, 1949, Serial No. 2,281

Term of patent 14 years

(Cl. D48—20)

To all whom it may concern:

Be it known that I, Leonard D. Cherneff, a citizen of the United States, residing at Seattle, in the county of King and State of Washington, have invented a new, original, and ornamental Design for a Combined Lamp Stand and Ash Tray, of which the following is a specification, reference being had to the accompanying drawings, forming part thereof. The characteristic features of this device are shown by full lines in the drawings.

In the drawings:

Figure 1 is a plan view of a combined lamp stand and ash tray, showing my new design.

Fig. 2 is a front elevational view of the same.

Fig. 3 is a side elevational view of the same.

I claim:

The ornamental design for a combined lamp stand and ash tray, as shown and described.

LEONARD D. CHERNEFF.
